UNITED STATES PATENT OFFICE.

BURT C. ALVORD AND CHARLES A. GILMER, OF LE GRAND, CALIFORNIA.

AIR MOISTENER FOR INTERNAL-COMBUSTION ENGINES.

Application filed January 5, 1921. Serial No. 435,183.

To all whom it may concern:

Be it known that we, BURT C. ALVORD and CHARLES A. GILMER, citizens of the United States, residing at Le Grand, county 5 of Merced, State of California, have invented certain new and useful Improvements in Air Moisteners for Internal-Combustion Engines; and we do declare the following to be a full, clear, and exact description of the same, reference being had to the accompanying drawings and to the characters of reference marked thereon, which form a part of this application.

This invention relates to improvements in 15 devices for injecting water or steam with the ingoing charge for an internal combustion engine.

Some provision however should be made to insure that the supply of steam or water 20 is proportional to the amount of fuel drawn into the engine, and to successfully accomplish this in an automatic manner forms the principal object of our invention.

Another object is to provide a device for 25 the purpose which may be used in connection with almost any make of carbureter, and is operated and controlled by the moving of the throttle or butterfly valve of the carbureter.

30 A further object of the invention is to produce a simple and inexpensive device and yet one which will be exceedingly effective for the purposes which it is designed.

These objects we accomplish by means of 35 such structure and relative arrangement of parts as will fully appear by a perusal of the following specification and claim.

In the drawings similar characters of reference indicate corresponding parts in the 40 several views.

Fig. 1 is a top plan view of the device, showing the same installed in connection with a certain form of carbureter.

Fig. 2 is a sectional elevation of the device, showing the method of automatically 45 controlling the flow of water by the throttle of the carbureter.

Fig. 3 is a fragmentary cross section of a spray-pipe taken on a line 3-3 of Fig. 2.

50 Fig. 4 is a cross section of the pipe taken on a line 4-4 of Fig. 3.

Referring now more particularly to the characters of reference on the drawings, the numeral 1 denotes the carbureter in general, 55 provided with the usual throttle valve 2 mounted on a stem 3, and with an air intake

portion 4 communicating with the body of the carbureter by a throat 5.

Our improved water-feed device consists of a cylinder 6, closed at both ends, and secured to the engine or the frame on which it is mounted by means of a clamp-bracket 7, the axis of the cylinder being preferably at right angles to the stem 3 of the carbureter and substantially in the vertical plane 65 of the stem adjacent its outer end.

The end of the cylinder nearest the carbureter is preferably formed as a removable cap 8 with which is formed an arm 9 extending lengthwise of the cylinder and away 70 therefrom and preferably positioned in alinement with the outer periphery of the cap.

Pivoted at the outer end of the arm 9 is a flat bar 10 extending across the plane of the 75 axis of the cylinder substantially at right angles thereto, being adapted to bear against a cam member 11 removably and adjustably mounted on the throttle valve stem 3 by means of a set screw 11a.

80 Formed integrally with the cap 8 and projecting outwardly therefrom is a concentric sleeve 12 in which is slidably mounted a taper-valve member 13 whose stem 14 projects from the outer end of the sleeve 85 and is arranged to press constantly against the bar 10 by reason of a spring 15 about the stem, which spring also tends to hold the valve 13 closed to prevent communication from the cylinder 6 to a pipe 16 which 90 connects with the sleeve 12 inwardly of the valve therein and extends over the carbureter at the throat 5 and is seated in a slot 17 cut therethrough, the under side of said pipe being provided with a line of small 95 holes 16a communicating with the interior of said throat, the outer end of the pipe being closed.

The outer end of the sleeve 12 is provided with a packing gland and nut as at 18, to 100 prevent any leakage of steam or water around the valve stem.

105 Communicating with the cylinder 6 at the end thereof opposite the valve 13 is a water pipe 19, while a removable screen-bowl 20 is positioned in the cylinder intermediate the ends and making close contact with the sides, so as to catch and hold any relatively large particles of foreign matter in the water from clogging up the valve 13 or getting into the pipe 16.

In operation, the cam is so positioned on

the stem 3 that when the valve 2 is closed the valve 13 is likewise closed.

Then as the said throttle valve is opened, the cam bears on the bar 10, which in turn 5 presses on the stem 14, opening the valve 13 in proportion to the amount of opening of the throttle, and admitting the water or steam to the pipe 16 and hence to the throat 5 of the carbureter, where it will mix with 10 the air being drawn in through the intake 4 prior to the mingling of the two with the kerosene or other fuel.

It will be noted that the bar 10 is a lever, whose fulcrum is at its point of connection 15 with the arm 9, and hence the amount the stem 13 is moved by the movement of the cam depends on the position of the cam on the stem 3. Thus by adjusting the position of said cam, the amount of opening of the 20 valve 13 and hence the quantity of water or steam admitted to the carbureter may be regulated to suit different conditions.

This condition may be obtained by any 25 suitable means, certain of which will be obvious.

The device while adaptable for use with any internal combustion engines, is especially suited for use in connection with tractor engines, which are called upon to work 30 for long periods at a stretch and under full

power, which not only tends to heat up the motor, but consumes a large quantity of fuel.

From the foregoing description it will be readily seen that we have produced such a 35 device as substantially fulfills the objects of the invention as set forth herein.

While this specification sets forth in detail the present and preferred construction of the device, still in practice such deviations from such detail may be resorted to and do not form a departure from the spirit of the invention, as defined by the appended claim.

Having thus described our invention, what 45 we claim as new and useful and desire to secure by Letters Patent is:

In combination with the air passage member of a carbureter provided with a transverse slot on one side, a water supply pipe 50 terminating in a portion seated in said slot, said portion being provided with a plurality of spray-holes along the face thereof projected into the slot, the end of the pipe being closed.

In testimony whereof we affix our signatures.

BURT C. ALVORD.
CHARLES A. GILMER.
